(57) **CLAIM**

The ornamental design for the golf club grip, as shown and described.

DESCRIPTION

FIG. 1 is a front elevational view of a first embodiment of the golf club grip of our design;

FIG. 2 is a side elevational view of the left side thereof;

FIG. 3 is a side elevational view of the right side thereof;

FIG. 4 is a rear elevational view thereof;

FIG. 5 is a top plan thereof;

FIG. 6 is a bottom plan view thereof;

FIG. 7 is a front elevational view of a second embodiment of the golf club grip of our design;

FIG. 8 is a side elevational view of the left side of FIG. 7;

FIG. 9 is a side elevational view of the right side of FIG. 7;

FIG. 10 is a rear elevational view of FIG. 7;

FIG. 11 is a top plan view of FIG. 7;

FIG. 12 is a bottom plan view of FIG. 7;

FIG. 13 is a front elevational view of a third embodiment of the golf club grip of our design;

FIG. 14 is a side elevational view of the left side of FIG. 13;

FIG. 15 is a side elevational view of the right side of FIG. 13;

FIG. 16 is a rear elevational view of FIG. 13;

FIG. 17 is a top plan view of FIG. 13; and,

FIG. 18 is a bottom plan view of FIG. 13.
